UNITED STATES PATENT OFFICE.

FERDINAND G. WELKE, OF SAN FRANCISCO, CALIFORNIA.

INTERNAL-COMBUSTION ENGINE.

1,335,947.

Specification of Letters Patent.

Patented Apr. 6, 1920.

Application filed August 2, 1919. Serial No. 314,859.

To all whom it may concern:

Be it known that I, FERDINAND G. WELKE, a citizen of the United States, residing at the city and county of San Francisco and State of California, have invented certain new and useful Improvements in Internal-Combustion Engines, of which the following is a specification.

The present invention relates to an internal combustion engine having a cylinder formed with its axis on the arc of a circle, and a piston, constrained to travel in an arcuate path within said cylinder, by a piston rod fulcrumed at a point lying at the center of said arc.

The objects of the invention are to reduce friction losses and wear to a minimum, by eliminating side thrust between the piston and the cylinder walls, and to provide means for cooling the piston by passing a circulating fluid through a chamber formed therein. These and other objects are accomplished by the novel construction herein-after described and herewith illustrated in its preferred form, but it is understood that changes may be made in said form and construction, within the scope of the claims hereto appended, without departing from the spirit of the invention.

In order to fully comprehend the invention, reference should be had to the accompanying drawings, in which—

Figure 1 is a longitudinal section, partly broken, of my engine, showing one cylinder with its piston, crank and associated parts.

Fig. 2 is a sectional detail of the piston rod fulcrum.

My engine is herewith illustrated and hereinafter described as having a single cylinder, although it is to be understood that any number of identical cylinders may be employed, each having a crank formed upon a common crank-shaft in the customary manner.

In the drawings, and referring particularly to Fig. 1 thereof, the reference numeral 1 designates the cylinder of my engine, said cylinder being formed with its axis lying in the arc of a circle. The upper end of the cylinder 1 is closed by a head 2. Suitable valves and ignition devices, of any well known form, and mechanism for operating the same, are provided, but inasmuch as said valves and ignition devices and operating mechanism form no part of the

present invention, they have been omitted from the drawings, except that a spark plug is indicated at 3. Likewise the cylinder 1 may be cooled in any suitable manner not illustrated.

Within the cylinder 1 is an arcuate piston 4, provided with suitable packing rings 5. Said piston is carried by a substantially L-shaped piston rod 6, whose end 7 is pivotally mounted upon a bearing pin 8 located at a point representing the center of the arc formed by the axis of the cylinder. Thus the piston is constrained to oscillate in an arcuate path whose curvature is coincident with that of the cylinder.

The pin 8 is carried in a crank case 9, shown as formed integrally with the cylinder 1. A crank 10 is carried by a crank shaft, not shown, but journaled in the walls of the crank case 9 in the usual manner. A connecting rod 11, journaled at 12 upon the piston rod 6 and at 13 upon the crank 10, connects said piston rod with the said crank.

It will be seen that the side thrust caused by the angularity of the crank and connecting rod is all taken by the fixed piston rod fulcrum pin 8, thus relieving the piston and cylinder walls of all such side thrust and the wear incident thereto.

On this account I am enabled to use a relatively short, and therefore light, piston, as shown, and furthermore, on account of the absence of side thrust and wear, I am enabled to make said piston gas-tight within its cylinder by means of but two rings, instead of the usual three or four.

The piston 4 is formed with an interior chamber 14, through which a cooling fluid may be circulated. A pair of pipes 15, one of which is shown in Fig. 1 and both in Fig. 2, in communication with said chamber, are carried along the sides of the piston rod 6, and connect, through passages 16, Fig. 2, formed in the enlarged journal boss 17 of said rod, with annular grooves 18 formed in the projecting ends of said boss. Said projecting ends are surrounded, in close-fitting relation, by stationary rings 19, having annular grooves 20 adapted to register with the grooves 18 of said boss, and pipes 21 are provided for conducting the cooling fluid to and from said stationary rings 19. Suitable means, not shown in the drawings, are provided for supplying said fluid, under sufficient pressure to

one of said pipes 21 and for leading it away from the other, to establish a circulation within the hollow piston.

Packing 22 is provided on both sides of the rings 19, that on the inside being held in grooves formed in shoulders 23 on the journal boss 17, and that on the outside by adjustable nuts 24 screwed upon the projecting ends of said boss.

10. Thus the passages for the circulating cooling fluid are entirely separate from the bearing of the piston rod, so that a cooling fluid other than lubricating oil may be used if desired.

15. It is to be noted that, on account of the fulcrumed oscillating piston rod, rigidly fixed to the piston, I am enabled to provide a closed circulatory system, for cooling said piston, with but two moving connections, 20 one for feed and one for discharge, viz. the connections formed by the grooved rings 19 and the piston rod boss 17.

Having thus described my invention, what I claim as new and desire to protect by Letters Patent is:—

1. In an internal combustion engine, a cylinder formed with a portion having its axis lying in the arc of a circle, and terminating in a cylinder casing, a piston operable within said arcuate cylinder portion, a piston-rod fixed to said piston at one end and at the other end pivotally mounted to a fulcrum arranged within said cylinder casing centrally of the arc of said cylinder, 35 a crank within said cylinder casing, and a connecting rod within said cylinder casing pivotally connected at opposite ends to said crank and piston rod for transferring oscillatory movement of said piston-rod to rotary 40 movement of said crank.

2. In an internal combustion engine, a cylinder formed with a portion having its axis lying in the arc of a circle and terminating in a cylinder casing, a piston rotatable within said arcuate portion of the cylinder in a fixed oscillatory path of travel, a crank within the cylinder casing and means for transmitting oscillatory movement of said piston to rotary movement of 45 said crank, all of said parts contained within and inclosed by said cylinder casing.

3. In an internal combustion engine, a cylinder formed with a portion having its axis lying in the arc of a circle and terminating in a cylinder casing, a piston operable within said cylinder, a crank, a connecting rod between said piston and said crank, and means for causing said piston to oscillate in an arcuate path coincident with the axis of said cylinder, all of said 60 parts contained within and inclosed by said cylinder casing.

4. In an internal combustion engine, a cylinder formed with its axis lying in the arc of a circle; a hollow piston operable within said cylinder; a piston rod rigidly fixed to said piston at one end and at the other end pivotally mounted centrally of the arc of said cylinder; a pipe associated with said piston rod and having communication with said hollow piston; means concentric with the pivot of said piston rod for establishing fluid connection with said pipe; a crank; and means for transmitting motion from said piston to said crank. 75

5. In an internal combustion engine, a cylinder formed with its axis lying in the arc of a circle; a chambered piston operable within said cylinder; a piston rod rigidly fixed to said piston at one end and at the other formed with an annularly grooved journal boss; a bearing pin, mounted centrally of the arc of said cylinder, and upon which said piston rod boss is journaled for oscillatory movement; a pipe associated with said piston rod and having communication at one end with the chamber of said piston and at the other with the groove of said boss; a grooved ring surrounding said boss and having its groove in registry with the groove of said boss; an exterior fluid connection leading to the groove of said ring; a crank; and means for transmitting motion from said piston to said crank. 85 90 95

In testimony whereof I have signed my name to this specification in the presence of two subscribing witnesses.

FERDINAND G. WELKE.
